Primary Examiner — Jack Reickel*Assistant Examiner* — Salamah Jordan(74) *Attorney, Agent, or Firm* — Hawaii Patent Services; Nathaniel K. Fedde; Kenton N. Fedde(57) **CLAIM**

The ornamental design for a sport handle, as shown and described.

DESCRIPTION

FIG. 1 is a front perspective view of a sport handle, showing my new design;

FIG. 2 is a rear perspective view thereof;

FIG. 3 is a front elevational view thereof;

FIG. 4 is a rear elevational view thereof;

FIG. 5 is a left elevational view thereof, the right elevational view is identical;

FIG. 6 is a top plan view thereof; and,

FIG. 7 is a bottom plan view thereof.
